FEEDING MEANS FOR UNDERFEED STOKERS

Forrest L. Hitchcock, Indianapolis, Ind., assignor
to FurnaSlave, Inc., Indianapolis, Ind.

Application August 16, 1934, Serial No. 740,129

10 Claims. (Cl. 198—221)

This invention relates to the art of stokers and particularly to means for feeding solid fuel into a combustion zone. A primary object of my invention is to provide a feeding means which will first of all feed fuel into the combustion zone freely without danger of becoming clogged or stopped by the fuel itself. The structure herein shown and described is particularly adapted to feed fuel ranging in size from the commercially termed pea size to the nut size. It is a further primary object of my invention to provide a feeding mechanism which will feed such type of fuel with the minimum noise so that, in the space to be heated, no noise will be perceptible, a slight noise, if any, arising by the passage of the fuel through the mechanism being blocked off or insulated from the member into which the fuel is fed for combustion.

A further primary object of my invention is to provide a fuel feeding mechanism wherein the fuel is not compacted within a tube but is moved along therethrough in relatively small quantities so that the tube is not completely filled at any time. A still further important object of the invention is to provide means for elevating the fuel from the conveying member into the combustion zone in such a manner that there is no tendency for the fuel to become clogged or packed together when it is turned from the horizontal direction to the vertical direction of travel.

There is further included in my invention the feature of employing a single unit to feed coal into and to convey ashes out of the unit within which the fuel is to be consumed all in a manner tending to utilize the minimum power and to operate with the minimum noise, but moreover to so coordinate the ash removal with the fuel feeding as to provide for the ashes being removed as accumulated without having to drive the mechanism at an excessive speed and without having to employ a variable mechanism in relation to the fuel feeding mechanism.

Another feature of my invention resides in the removal of the ashes from the unit in which the fuel is burned and conducting such ashes to a desired depository either sunk below the floor level or placed thereabove.

These and other objects and advantages of the invention will become apparent to those skilled in the art in the following description of the invention as illustrated by the accompanying drawings, in which

Fig. 1 is a central, longitudinal, vertical section through a structure embodying my invention;

Fig. 2, a vertical transverse section on the line 2—2 in Fig. 1;

Fig. 3, a vertical transverse section on the line 3—3 in Fig. 1;

Fig. 4, a top plan view with fragments of the enclosing walls broken away to disclose interior parts;

Fig. 5, a vertical transverse section on the line 5—5 in Fig. 4, illustrating a modified form of ash conveyor;

Fig. 6, a central vertical longitudinal section through a feeding mechanism in modified form;

Fig. 7, a transverse central section through the modified structure, and

Fig. 8, a transverse vertical section on the line 8—8 in Fig. 6.

Like characters of reference indicate like parts throughout the several views in the drawings.

I provide a main housing 10 which has a top opening 11 into which fuel may be dropped. This housing 10 is principally rectangular in vertical cross section and is provided with an up-turned L 12 at the discharge end which has a circular cross section. There is an off-set between the juncture of the L 12 with the housing 10 as indicated in Fig. 3 and the under side of the L 12 is continued back under the housing 10 for a short distance to provide a base on which a head 13 may slide.

This head 13 is curved on its under side to conform to the curvature of the floor of the L and is provided with a longitudinal slot to receive therein the guide 14 which is fixed on the floor of the L 12 to prevent circumferential travel of the head 13 around the floor. The guide 14 serves a further purpose in that its forward end serves as a stop against which fuel may rest as will be further described hereinbelow.

On the upper side of the head 13 and spaced rearwardly from the forward end thereof is a floor 15 which fits slidably between the side walls of the housing 10 and extends rearwardly under and beyond the opening 11. The front end of the floor 15 is secured to the head 13 while the rear end of the floor rests upon a transversely disposed plate 16 so that the floor is supported at each end thereof to be substantially horizontal. A step plate 17 is secured to the upper side of the floor 15 at the rear end thereof, Fig. 1, to extend forwardly under the opening 11 in the housing 10. A connecting rod 18 pivotally interconnects with the head 13 and extends rearwardly under the floor 15 into a power transmission box 19 which is operated by a motor 20 to give suitable horizontal reciprocating motion to the rod 18. The ex-

55

act details of the power transmission included in the box 19 are not here shown since they do not specifically enter into my invention.

The vertical walls of the housing 10 are provided with inwardly extending portions 21 and 22 the upper edges of which are stepped downwardly from the rear to the forward end of the housing to provide a series of shoulders 23 at decreasing elevations as the forward end of the housing is approached. The forward end of the head 13 is sloped upwardly and rearwardly and likewise the forward end of the guide 14 is sloped upwardly and rearwardly.

The L 12 has an increasing cross sectional diameter as it leaves the end of the housing 10 and turns around upwardly. Preferably the upward extension of the L is broken to have a separate pipe 24 fixed thereto and extending on upwardly into the desired combustion zone. This separate extension 24 is provided so that it may be connected to the discharge end of the L in a manner permitting some means of insulation to be incorporated therebetween so as to prevent transmission of sound from the L to the member 24 thereabove. In the particular form herein shown, this insulating means comprises a gasket 25 placed between the member 24 and the L 12, insulating thimbles 26 placed around the bolts 27 which pass through the flanges of the two members 24 and 12 and insulating washers between the head and nut of each bolt to bear against the flanges of those members.

Below the housing 10 and extending somewhat outwardly from each side thereof are disposed two ash conveying screws 28 and 29 supported to be revolved about their longitudinal axes. The forward ends of these screws extend out along the side of the L 12 in the open while the rear and major portions thereof extend back within housings 30 and 31 extending outwardly from the base of the housing 10 and around and under the screws. A shaft 32 extending from the transmission box 19 carries a sprocket 33 thereon around which a conveyor chain 34 is wrapped to extend downwardly and around sprockets on each of the screws 28 and 29 and thence back up to the sprocket 33 again. By means of this chain 34, the two screws are driven, and also the ashes being carried back by the screws toward the chain 34 are scraped along the floor 35 to the elevator chain 37, Fig. 5. When the ashes are to be placed in a receptacle sunk in the floor, the ashes will be discharged through an opening 36 directly from the screws into the receptacle which may be placed thereunder and the scraper blades on the chain 34 are then omitted.

In practice, the forward end of the structure above described is inserted within the furnace or unit to which fuel is to be fed to have the L 12 and the forward portion of the housing 10 at least back to that part where the screws 28 and 29 are covered over all within the ash pit or below the grates of the furnace or unit. Now as fuel is fed into the opening 11, it drops downwardly to strike the plate 17 and also the floor 15. Since the floor 15 and its plate 17 fit with a rather close fit between the lower ends of the sides of the housing 10, the fuel will be retained on the floor and the plate. The floor 15 is given a fore and aft reciprocatory motion through the rod 18 so that as the floor 15 moves forwardly, fuel will be carried along therewith on the forward travel of the floor and will then tend to remain in that forward position by reason of friction on the side walls or rather the extending portions 21 and 22 there-

on and further by reason of the fuel engaging against the shoulders 23 upon the initial return movement of the floor 15. Thus the floor 15 and step plate 17 may return rearwardly and then again upon the forward stroke, carry the fuel forwardly again. The fuel will drop down in front of the head 13 upon the return stroke. The succeeding feeds of fuel are facilitated by forward pressure of the step plate 17 thereagainst. While this plate 17 tends to push the fuel forwardly the floor 15 being perfectly smooth over its major length will slip readily out from under the fuel so that additional fuel may be fed in front of the step plate 17 and be carried forwardly again on the next forward stroke. Simultaneously with this conveying of the fuel forwardly through the housing 10, the forward end of the head 13 is intermittently pushing the fuel up around the L 12 until the L is completely filled so as to provide a foundation to support a column of fuel being urged up through the extension 24. The top level of the fuel within the housing 10 will rarely, if ever, be above the rear shoulder 23 so that a clearance is left between the upper side of the fuel and the top of the housing 10. While it was stated above that the head 13 intermittently pushed the fuel ahead to fill the L 12, that L is not completely filled and the fuel therein is built up to have the rear part thereof follow some such contour as indicated by the dash lines, Fig. 1.

It is to be particularly noted that the head 13 pushes forwardly on the under side of the fuel only. The length of the stroke of the head 13 is such that its forward end will just come about even with the front end of the guide 14. Now as the head 13 returns rearwardly, the fuel within the L is prevented from falling back down principally by the fuel bank thereunder aided by the forward end of the guide 14 serving as a stop to prevent the fuel from sliding rearwardly. By reason of the fact that the fuel is fed into the L 12 in the manner stated by the head 13 and also by reason of the fact that the L 12 is tapered, the fuel is fed around the bend without tending to become clogged, or impacted therein. The speed at which the floor 15 is reciprocated determines the rate of feed of fuel through the L 12.

Ashes are permitted to drop down freely around the L 12 and the forward end of the housing 10 to build up therearound sufficiently to permit the screws 28 and 29 to be fed by the ashes sliding theretoward so that as the screws revolve, they will feed the ashes back along under the housing 10 through the laterally extending housings 30 and 31 where the ashes may be eventually dropped through the opening 36 as above indicated. The shape of the screws 28 and 29 and their rate of travel are so predetermined that the ashes as formed will be withdrawn at a sufficient rate of speed to keep the ashes removed without building up unduly around the L 12 and housing 10. In other words, these elements are so designed as to be operative in accordance with the feed of fuel by the floor 15.

Where it is not desired to drop the ashes through an opening into a receptacle below the feeding mechanism, some elevating device may be employed as indicated in Fig. 5 where the conveyor chain 37 may carry the ashes around up a conveyor floor 38 to elevate them sufficiently high to permit them to drop out of the elevator at some upper elevation over a receptacle. It is preferred at all times to arrange the ash con- 75

veyor so that it may discharge directly over a receptacle which may be enclosed, particularly dust tight, so that as the ashes drop therein, the dust will be confined within the receptacle and the elevator, the elevator being suitably connected with the receptacle closure so as to retain the dust and prevent its escape into the room.

Where a smaller unit is desired, a modified form of the structure may be employed such as is shown in Figs. 6, 7 and 8. In this modified form, a housing 40 is employed which has a circular cross section. Fuel is fed into the housing 40 through the entry 41 where it may drop in front of a plunger 42. This plunger 42 reciprocates rearwardly and forwardly but never entirely across the entry 41, the forward limit of travel being approximately that position as indicated in Fig. 6. The upper forward face of the plunger is preferably sloped rearwardly. A pair of guides 43 and 44 are fixed within the housing 40 to extend longitudinally therealong and toward the bottom thereof and the plunger 42 is notched out to fit over these guides so that the plunger 42 may be reciprocated freely thereover and be prevented from circumferentially revolving within the housing 40.

These guides 43 and 44 extend beyond the forward limit of travel of the plunger 42 and serve as fuel stops as will be hereinafter more fully indicated. Fixed to opposite sides of the plunger 42 are fingers 45 and 46 which extend horizontally forwardly throughout substantially the entire length of the housing 40 and terminate with beveled ends. Both of these fingers 45 and 46 are provided with shoulders 47 and 48 respectively about half way of their length ahead of the plunger 42, these shoulders being formed as herein shown by placing bars 49 and 50 on the inner faces of the fingers 45 and 46 to have the forward ends of such bars forming the shoulders 47 and 48. These shoulders are left square and not beveled. Also a finger 51 is fixed to the under side of the plunger 42 and extends forwardly along the floor or bottom of the housing 40 to terminate with a beveled end in the plane of the ends of the side fingers 45 and 46. This finger 51 is also provided with a shoulder 52 substantially at its midway ahead of the plunger 42, the shoulder 52 being formed by the end of a bar 53 which is fixed to the finger 51 to extend rearwardly back to the plunger 42.

The forward end of the housing 40 is turned around from the horizontal to extend upwardly and has an extended feed pipe 54 fixed thereto, preferably in an insulated manner such as above described.

In this modified form, being a smaller unit, but one ash conveying screw 55 is employed and this screw is centrally mounted under the housing 40 to be carried by a bearing at its forward end and extending back through a tubular housing 56 suspended under the housing 40. A conveyor chain 57 is driven by a sprocket 61 on the screw 55 to extend to any desired position so as to discharge the ashes brought to the chain by the screw 55. When the ashes are to be dropped through an opening 62 in the bottom of the housing 56, then the sprocket 61 and chain 57 are dispensed with.

In operation, the fuel is dumped through the entry 41 into the housing 40 at such rate that the entry is not completely filled up and the plunger 42 through its repeated reciprocations may carry the fuel forwardly within the housing 40 without completely filling that housing. As

the plunger 42 moves forwardly against the fuel, the fingers 45, 46 and 51 move forwardly also and by reason of their forward ends and the shoulders 47, 48 and 52 carried thereby push the fuel forwardly step by step and push it around the L at the end of the housing 40 so as to elevate the fuel into the extension 24. As the plunger 42 withdraws or moves rearwardly, the fingers may be "stripped" from the fuel which is prevented from following by reason of the forward blunt ends of the guides 43 and 44 being present and by reason of the fuel resting on the wall of the housing 40. The plunger 42 is reciprocated by a connecting rod 58 which is driven through a suitable transmission device within the housing 59 by a motor 60.

Both forms of the feeding mechanism above described are particularly well adapted for feeding coke. The feeding mechanism is also particularly adapted to underfeed grates of the type indicated in my copending application for U. S. Letters Patent Serial No. 725,557, filed May 14, 1934.

While I have herein shown and described my invention in the best forms as now known to me, it is obvious that structural variations may be made without departing from the spirit of the invention and I, therefore, do not desire to be limited to the precise forms as herein shown and described nor any more than may be required by the following claims.

I claim:

1. In a solid fuel stoker feeding device, a fuel directing housing, an L on the discharge end of the housing, a reciprocable member within and on the underside of the housing for pushing fuel along in the housing and into said L, said member being formed to move a volume of fuel less in height than that of the interior of the housing so that a free space is maintained in the housing above the fuel therein, and fixed stops on the interior of the housing tending to strip said member of fuel upon its return stroke.

2. In a solid fuel stoker feeding device, a fuel directing housing, an L on the discharge end of the housing, a reciprocable member within and on the underside of the housing for pushing fuel along in the housing and into said L, said member being formed to move a volume of fuel less in height than that of the interior of the housing so that a free space is maintained in the housing above the fuel therein, and fixed stops on the interior of the housing tending to strip said member of fuel upon its return stroke, said member comprising an elongated finger, and a head carrying the finger, said housing having an opening through which fuel enters, and said head being placed to move over at least a part of said opening to push fuel away therefrom.

3. In a solid fuel stoker feeding device, a fuel directing housing, an L on the discharge end of the housing, a reciprocable member within and on the underside of the housing for pushing fuel along in the housing and into said L, said member being formed to move a volume of fuel less in height than that of the interior of the housing so that a free space is maintained in the housing above the fuel therein, and fixed stops on the interior of the housing tending to strip said member of fuel upon its return stroke, said member comprising an elongated finger, and a head carrying the finger, said housing having an opening through which fuel enters, and said head being placed to move over at least a part of said opening to push fuel away therefrom, and addi-

tional fingers carried by said head extending within and along the sides of said housing.

4. In a solid fuel stoker feeding device, a fuel directing housing, an L on the discharge end of the housing, a reciprocable member within and on the underside of the housing for pushing fuel along in the housing and into said L, said member being formed to move a volume of fuel less in height than that of the interior of the housing so that a free space is maintained in the housing above the fuel therein, and fixed stops on the interior of the housing tending to strip said member of fuel along its return stroke, said member comprising the floor of the housing, a head fixed on the discharge end of the floor spacing the floor above the floor of the L and having its forward face below the floor, and a stop substantially at the juncture of the end of the curved floor of the L and a horizontal apron extending rearwardly therefrom, said stop being forward of the head when it is back of its forward limit of travel.

5. In a solid fuel stoker feeding device, a fuel directing housing, an L on the discharge end of the housing, a reciprocable member within and on the underside of the housing for pushing fuel along in the housing and into said L, said member being formed to move a volume of fuel less in height than that of the interior of the housing so that a free space is maintained in the housing above the fuel therein, and fixed stops on the interior of the housing tending to strip said member of fuel along its return stroke, said member comprising the floor of the housing, a head fixed on the discharge end of the floor spacing the floor above the floor of the L and having its forward face below the floor, and a stop substantially at the juncture of the end of the curved floor of the L and a horizontal apron extending rearwardly therefrom, said stop being forward of the head when it is back of its forward limit of travel, and a series of stepped inwardly projecting shoulders on the side walls of the housing above said floor.

45 6. In a solid fuel stoker feeding device, a fuel directing housing, an L on the discharge end of the housing, a reciprocable member within and on the underside of the housing for pushing fuel along in the housing and into said L, said member being formed to move a volume of fuel less in height than that of the interior of the housing so that a free space is maintained in the housing above the fuel therein, and fixed stops on the interior of the housing tending to strip said member of fuel along its return stroke, said member comprising the floor of the housing, a head fixed on the discharge end of the floor spacing the floor above the floor of the L and having its forward face below the floor, and a stop substantially at the juncture of the end of the curved floor of the L and a horizontal apron extending

rearwardly therefrom, said stop being forward of the head when it is back of its forward limit of travel, and a step on the rear upper side of the floor, said step being located under a fuel receiving opening in said housing, whereby said step upon reciprocating travel of the floor will hold the fuel stationary on the floor in the forward travel but may slip out thereunder upon rearward travel.

5 7. In a solid fuel stoker feeding device, a fuel directing housing, an L on the discharge end of the housing, a reciprocable member within and on the underside of the housing for pushing fuel along in the housing and into said L, said member being formed to move a volume of fuel less in height than that of the interior of the housing so that a free space is maintained in the housing above the fuel therein, and fixed stops on the interior of the housing tending to strip said member of fuel upon its return stroke, a fuel conducting pipe supported by said L, and sound insulating means interposed between the pipe and L and said L flaring from said housing whereby in conjunction with free movement of fuel through the L and said insulation, crushing and grinding sound of the moving fuel is not transmitted to said pipe.

10 8. In a solid fuel stoker feeding means, a fuel directing housing, reciprocating means for carrying fuel along the bottom of the housing, and fuel return stop means comprising stationary shoulders on the housing ahead of and at the sides of said reciprocating means holding fuel in a forward position during return travel of said reciprocating means.

15 9. In a solid fuel stoker feeding means, a fuel directing housing, reciprocating means for carrying fuel along the bottom of the housing, and fuel return stop means comprising stationary shoulders on the housing ahead of and at the sides of said reciprocating means holding fuel in a forward position during return travel of said reciprocating means, and an upturned L on the discharge end of the housing, said reciprocating means being formed to feed fuel into the L along 40 and around the underside thereof.

20 10. In a solid fuel stoker feeding means, a fuel directing housing, reciprocating means for carrying fuel along the bottom of the housing, and fuel return stop means comprising stationary shoulders on the housing ahead of and at the sides of said reciprocating means holding fuel in a forward position during return travel of said reciprocating means, and an upturned L on the discharge end of the housing, said reciprocating 45 means being formed to feed fuel into the L along and around the underside thereof, said L having a cross-sectional area at its juncture with the housing less than that of the housing, said area increasing around the L.

25 50 55 60 FORREST L. HITCHCOCK.
